UNITED STATES PATENT OFFICE.

LEWIS B. AVERY, OF BRIDGEWATER, MICHIGAN.

REIN-GUARD.

1,077,327.

Specification of Letters Patent.

Patented Nov. 4, 1913.

Application filed June 23, 1913. Serial No. 775,446.

To all whom it may concern:

Be it known that I, LEWIS B. AVERY, a citizen of the United States, residing in the township of Bridgewater, in the county of 5 Washtenaw and State of Michigan, have invented a new and useful Improvement in Rein-Guards, of which the following is a specification.

The object of this invention is, to provide 10 a simple, inexpensive, and permanently attachable rein-guard that will prevent the cross-lines of a double harness from getting under the end of the tongue of the wagon on which it is used by extending laterally each 15 way from the end of the tongue back to the neckyoke and ordinarily about six inches each way from the center of the neckyoke. I attain this object by the mechanism illustrated in the accompanying drawing, in 20 which—

Figure 1 is a plan view of the guard when in use; and Fig. 2 is a full size view on the line x y in Fig. 1 of the bearing that holds the guard in place.

25 When no guard is used, and the team is standing and the lines are hanging loosely, either of the inside-lines is likely to sag and swing under the end of the tongue and to bind there when the driver pulls up on it, 30 making it difficult for him to guide his team until some one goes to the front of the team and pulls the line out. This happens very frequently when the team is stopped and started very often, as when driving from 35 one shock of grain to another, and stopping and hanging the lines on the front standard while each shock is being loaded. A driver will sometimes have to get down from a high load and take a line out from under 40 the tongue and climb back up again before he can drive his team satisfactorily. But when this device is used, it will, by its peculiar shape and position, effectually prevent the lines from getting under the end of 45 the tongue.

This guard consists essentially of a hoop 1 made of heavy stiff wire, and has a diameter of about twelve inches, more or less, and is situated over the end of the tongue 11 and under the neckyoke 14, its center being under the center of the neckyoke 14. In Fig. 1, the middle portion of the neckyoke 14 is broken away to show the central portion of the guard when in place, the neckyoke ring 13 being left in position on the tongue. The ends of the wire forming the

hoop 1 are welded together, as at 10, or are twisted together there so as to form a stiff joint. About midway across the right and left halves of the hoop 1, two wires 2' 2 extend, the ends of each being bent tightly around the hoop wire. These wires are also joined near their centers by two parallel wires 4 4', which, with the wires 2' 2, form a rectangular slot through which the neckyoke ring and links may easily pass. Short wires 9 9 join the wires 2' 2 with the hoop 1 so as to strengthen the whole structure. The wires 4 4' also carry a bearing 5 which holds the guard in place. This bearing is 60 formed of wire and has two loops 7 7 which are adapted to rest upon the upper portion of the ring 13. The ends 8 8 of the wire forming the bearing are bent loosely around wire 4', so that the bearing may be swung 65 around it. The middle portion of the wire forming the bearing is bent to form a forwardly- and upwardly-extending loop 6, which rests against the wire 4 and helps to keep the bearing in position. 70

To prevent the front portion of the guard from dropping down in front of the end of the polecap loop 12, a wire joins the wires 2 2' near their front ends. A similar wire 3' joins them near their opposite ends also, 75 and serves the same purpose when the positions of the neckyoke and guard are reversed. 80

The ends of the wires 3 3', 4 4', and 9 9 are bent tightly around the wires 2 2', or are welded or otherwise secured to them, so as 85 not to slip; and in the same way, the ends of the wires 2 2' and 9 9 are bent tightly around the hoop wire 1.

When no guard is used, either cross-line, for example, the left one 15, if it gets under 90 the tongue, would be about in the position shown by the dotted lines 15'; but when this guard is used, the line can do no more than to sag down to one side of the guard, as shown at 15, and can be easily pulled up 100 again.

This guard, when attached to the neckyoke, may remain there during a harvest season, or all the year around, as the owner may see fit. 105

To attach the guard to the neckyoke, the neckyoke ring 13 is dropped through the slot formed by the wires 2 2' and 4 4', when the bearing 5 is inserted over the ring 13 and under the neckyoke 14, and the loop 6 110 is sprung under the wire 4. It will then remain in this position unless forced out of it.

Either side of the guard and consequently either side of the neckyoke may be in front; and the guard will, in either case, work equally well. Thus no care need be taken as to which side of the neckyoke or of the guard is placed in front.

Instead of a hoop or ring, a sheet-metal disk of the same size as the hoop and with a slot through its center might be used to 10 accomplish the same purpose; and whether a hoop or a disk be used, it need not necessarily be circular in form, but is to be shaped so as to extend backwardly and laterally each way from the end of the polecap loop 15 12 toward the neckyoke so as to prevent the cross-lines from getting under it.

I claim as my invention—

1. A flat-shaped rein-guard, whose central portion is situated beneath the middle 20 portion of the neckyoke on which it is used, having a slot through its center to admit the passage of the neckyoke ring and links, and whose forward edge extends laterally each way from near the front end of the tongue 25 and backwardly toward the under side of the neckyoke to prevent the cross-lines, when sagging, from getting under the end of the tongue.

2. A rein-guard consisting of a ring or

30 hoop having a slot through its central portion formed by cross-wires secured to its periphery and large enough to permit the neckyoke ring and links to pass through it, and whose central portion is situated beneath the middle portion of the neckyoke on 35 which it is used, and whose diameter is such that its forward half will extend over the most of that portion of the tongue that is in front of the neckyoke, substantially as shown and described and for the purpose 40 specified.

3. A rein-guard consisting of a ring or 45 hoop having a slot through its central portion formed by cross-wires secured to its periphery and large enough to permit the neckyoke ring and links to pass through it, and having a bearing hinged to one of the cross-wires forming said slot, and fitted to 50 and capable of resting on the upper side of the neckyoke ring and terminating in a loop which extends beyond and rests against the under side of the opposite cross-wire, substantially as shown and described and for the purpose specified.

LEWIS B. AVERY.
